(57) **CLAIM**

The ornamental design for a faucet spout, as shown and described.

DESCRIPTION

FIG. 1 is a perspective view of our new design for a faucet spout;

FIG. 2 is a front elevation view;

FIG. 3 is a rear elevation view;

FIG. 4 is a right side elevation view, the left side being a mirror image thereof;

FIG. 5 is a top plan view; and,

FIG. 6 is a bottom plan view.

The broken lines in the Figures are for illustrative purposes only and form no part of the claimed design.
